UNITED STATES PATENT OFFICE.

PETER E. MORAN, OF PERRY, IOWA.

TRAP GRAIN DOOR.

Application filed September 11, 1922. Serial No. 587,350.

To all whom it may concern:

Be it known that I, PETER E. MORAN, a citizen of the United States, and a resident of Perry, in the county of Dallas and State 5 of Iowa, have invented a certain new and useful Trap Grain Door, of which the following is a specification:

The object of my invention is to provide a trap grain door for use in connection with 10 grain elevators, the parts being of simple, durable and comparatively inexpensive construction.

Still another object is to provide manually operable means for opening the trap 15 door.

Still another object is to provide means so that when a two part trap door is opened, the parts will lie in such position as will permit the wagon containing the grain to pass 20 thereover. In this connection it may be mentioned that the body of the vehicle containing the grain usually projects back over the door. When the door is comparatively large, it is necessary to make it of two parts 25 hinged together, so that one part will rest against the other so as to permit it to be raised under the wagon or body of a truck.

Still another object is to provide a structure 30 operable by the raising and lowering of the door member for causing one part thereof to move to position where it will rest against the other part, when in raised position, and causing it to be moved to position 35 where it will lie in the same plane and completely close the opening in the floor structure.

With these and other objects in view, my 40 invention consists in the construction, arrangement and combination of the various parts of my device, whereby the objects contemplated are attained as hereinafter more fully set forth, pointed out in my claims and illustrated in the accompanying drawings, 45 in which:

Figure 1 is a plan view of portions of the floor of a grain elevator with my improved structure shown thereon.

Figure 2 is a longitudinal, sectional view 50 taken on line 2—2 of Figure 1.

Figure 3 is a transverse sectional view taken on line 3—3 of Figure 2; and

Figure 4 is an enlarged sectional view 55 through the door, taken on line 4—4 of Figure 1.

In the accompanying drawings, I have

used the reference numeral 10 to indicate generally the supporting beams for the floor 11. In the floor 11 is provided a door opening through which the grain from the vehicles is dumped into the bin below the floor, from whence it is taken by a set of endless 60 elevator buckets up into the elevator proper.

Received within the door opening in the floor 11 is a door member, which comprises 65 the sections 12 and 13. The section 12 has hinge straps 14 fixed thereto. Fixed to the floor 11 adjacent the straps 14 are the corresponding straps 15. The straps 14 and 15 have projecting ends which are provided 70 with registering eyes. Through these eyes is received a rod 16, which is fixed securely to the hinge members 14 by means of pins 17.

The structure just described serves to hinge the section 12 to the floor. The sections 12 and 13 are hinged together on their under side by hinges 18.

Two bearing plates 19 are securely fastened to the floor 11 at each side of the door opening, and extend approximately the 80 length thereof. Brackets 20 are provided at the outer corners of the section 13, which serve to rotatably mount two rollers 21.

The edge of the floor adjacent to the door opening is provided with inclined side edges 85 22 so that any grain will slide in through the door opening.

The edge of the door members 12 and 13 are correspondingly inclined so as to be received against the inclined edges 22 of the 90 floor 11. In this connection, it may be mentioned that the inclined edges 22 of the floor 11 tend to support the door member 12.

The beams 10 are so arranged that the door member 12 rests thereon and in order 95 to prevent any grain from lodging upon the beams 10, the upper edges thereof below the door are sharpened, as at 23, so that the grain will not become lodged thereon.

The purpose of providing the two-part 100 door is for permitting wagons or other suitable vehicles to pass thereover when it is in its raised position, as shown in dotted lines in Figure 2 of the drawings.

The wheels of the wagon rest upon each 105 side of the door opening and upon the floor 11. If the two part door were not provided, then the door of sufficient size to accommodate the grain would extend up so far that it would be engaged by the wagon. 110

I will now explain the structure employed for raising and lowering the door member

12 and for properly positioning the member B relative to the member A.

One end of the rod 16 has a downwardly projecting crank arm 24, which projects 5 through a slot in the floor 11.

Pivoted to the crank arm 24 near the bend therein are the parallel spaced levers 25, which project downwardly and away from the arm 24 when the door is in its closed 19 position. Pivoted between the levers 26 at their free ends, is a pulley 27.

Secured to the floor 11, parallel to the beams 10, and positioned adjacent the slot 25 between said slot and the door opening, 15 is a joist 28. Pulleys 29 and 30 are rotatably mounted on the joist 28. A lever 31, having a weighted head 32 at its free end, is pivoted to the joist 28. The lever is so positioned that when it is raised toward a horizontal position, the head 32 will approach the pulley 30. 25

A cable 33 is fastened to the end of the arm 24, extends around the pulley 27, over the pulleys 29 and 30, and is fastened to the lever 31 near the head 32. The cable 33 is of such length that when the door is closed, the lever will be in its raised position. The lever is of such length that when the door is in position shown in dotted lines, 30 the lever will have swung downwardly close to a vertical position, as illustrated.

The purpose of the levers 26 is to keep that portion of the rope which is fastened to the lever 24, in order that the pull against 25 the arm may not vary materially. The use of the levers 26 also allows the arm 24 to swing through a greater angle than would be otherwise practical.

As the arm 24 is moved from its full line 40 position to its dotted line position, the levers 26 will first close over the arm 24 similar to the closing of a jackknife, during a portion of the movement and the three will move together as a unit during the remainder of the movement.

In order that the lever 26 may be stopped in its proper position while moving downwardly, a hook 34 is provided which slides in a bearing 35 on the inner lever 26. The 50 hook 34 is pivoted to the joist 28 in such position as to occupy, when the levers 26 are in their lowered position, approximately an arc of a circle having the rod 16 as a center. It is of the correct length to stop the levers 55 26 when they are somewhat past a position midway between closed and open positions of the arm 24.

A handle rod 36 is linked to the door member 12, by means of an eye 37. The head 32 is of such weight as to almost 60 balance the weight of the door. By pulling the rod 36, it will be seen that the door may be raised with very little effort. As the door is raised, the rollers 21 will support the weight of the section 13 while travelling over 65 the plates 19.

It will be seen that I have provided a very efficient device for opening the door and for causing the two parts thereof to so move that they will not interfere with any vehicle 70 passing thereover.

In this connection, it may be mentioned that a single piece door may be used, which is comparatively narrower than the rollers 21 75

Some changes may be made in the construction, and arrangement of the various parts of my invention, without departing from the real spirit and purpose of my invention and it is my intention to cover by 80 my claims, any modified forms of structure or use of mechanical equivalents, which may be reasonably included within their scope.

I claim as my invention:

1. A door structure of the class described 85 including a door member hinged at one end, a lever secured to said door member on the under side thereof, a weighted arm hingedly mounted, a flexible element secured to said lever at one end and to the weighted 90 arm at the other end, a guide pivotally mounted on said lever and capable of movement relative thereto over which said flexible element travels and a flexible element operable for causing the weighted arm to 95 swing on its hinge for the purposes stated.

2. A door structure of the class described including a two part door member hinged at one end, a support for the door member, the two parts of the door member being 100 hingedly connected together, a lever secured to one part of the door member, a weighted arm swingingly mounted, a flexible element connecting said lever with said arm, a guide for said flexible element pivotally mounted 105 on said lever, means for limiting the movement of the guide in one direction and means for causing one part of the door member to rest against the other when in one position and for causing it to move to position 110 where it will be in the same plane when in another position.

Des Moines, Iowa, September 7, 1922.
PETER E. MORAN.
